UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

INKING MECHANISM FOR BED-AND-CYLINDER PRINTING-PRESSES.

1,073,836.

Specification of Letters Patent.

Patented Sept. 23, 1913.

Application filed December 15, 1910. Serial No. 597,539.

To all whom it may concern:

Be it known that I, HOWARD M. BARBER, a citizen of the United States, and resident of Stonington, in the county of New London and State of Connecticut, have invented a new and useful Improvement in Inking Mechanism for Bed-and-Cylinder Printing-Presses, of which the following is a specification.

The object of this present invention is to provide a novel inking mechanism for bed and cylinder printing presses in which the rollers are always driven in the same direction and in which a continuous even distribution of the ink on the form is obtained, the ink always being worked in one direction and the form rollers always being in contact with the vibrators during both the printing and return strokes of the bed for insuring a thorough distribution of the ink on the form rollers.

In the accompanying drawings, Figure 1 represents in side elevation so much of a bed and cylinder printing press as will give a clear understanding of the invention. Fig. 2 is a detail section through the inking mechanism. Fig. 3 is a detail section showing certain of the geared connections. Fig. 4 is an inverted section taken in the plane 30 of the line A—A of Fig. 2, and Fig. 5 is a detail view showing more clearly the means for vibrating the rolls 13, 14, and the ink cylinder 6.

The sheet delivery mechanism and the mechanism for reciprocating the form bed are not shown herein as they form no part of the present invention and will not assist in a clear understanding thereof.

The reciprocating bed is denoted by 1, the form thereon by 2, the impression cylinder by 3, the fountain roller by 4, the ductor roller by 5, the ink cylinder by 6, the distributing and carrying rollers by 7, 8, 9, 10, 11, 12, the vibrators by 13, 14 and the form rollers by 15, 16, 17, 18.

The main drive shaft is indicated at 19, which shaft drives the cam shaft 26 through the gears 20, 21, 22, 23, 24, 25. The cams for controlling the movements of the fountain roller 4 and the ductor roller 5, are denoted by 27, 28, respectively, and their shaft by 29, which shaft is driven from the cam shaft 26, through the gears 25, 30, 31, 32, 33, 34. The impression cylinder 3 is driven from the drive shaft 19, through the gears

20, 21, 35, 36. The ink cylinder 6 is driven from the impression cylinder gear 36, through the gears 38, 39, 40, 41, and the vibrators 13, 14, are driven from the ink cylinder gear 41, through the gears 42, 43 and 44, 45 respectively. 60

The form rollers 15, 16, 17, 18, are mounted in bearings 46, 47, 48, 49 on rocking arms 50, 51, 52, 53 located at opposite ends of the roller shaft. The arms 50, 51, are 65 loosely mounted on the shaft of the vibrator 13, and the arms 52, 53, are loosely mounted on the shaft of the vibrator 14, so that as these arms are raised and lowered by the mechanism to be immediately described, the 70 form rollers will be at all times in contact with their respective vibrators. A cam 54 controls the raising and lowering of the form rollers 15, 16, 17, 18, as follows: A cross shaft 55 has fixed thereto an arm 56 75 having a stud or roller 57, engaged by the cam 54. At each side of the machine, this shaft 55 has fixed thereto an arm 58. Three angle levers 59, 60, 61, have their corresponding arms connected by a rod 62, for 80 causing these arms to be rocked in unison. The other corresponding arms of these angle levers are connected to the free ends of the arms 51, 52, 53, by rods 63, 64, 65, the rod 63 being connected to the arm 50, the 85 rod 65 to the arm 53 and the rod 64 to both the arms 51, 52. These angle levers are rocked by connecting one of the levers to the arm 58, by a rod 66. The cam 54 on the shaft 26 is so timed that the form rollers 90 will be lowered into contact with the form 2, during the forward printing stroke of the bed and will be raised to clear the form during the return stroke.

The rolls 13, 14, and the ink cylinder 6 95 may be vibrated by any desired means such as that shown in the accompanying drawings in which the shaft 6* of the ink cylinder 6 is reciprocated longitudinally by the worm 67 and worm wheel 68. The shaft 100 13*, 14*, are reciprocated longitudinally by the rocking levers 69, 70, from the ink cylinder shaft 6*. It will be seen that these form rollers are always driven in one direction by their contact with the vibrators, 105 thus accomplishing the following results: first, the working of the ink in one direction; second, a continuous even distribution, and third, the ability of the machine to be successfully run at a higher rate of speed 110

because of the non-reversing movement of said rollers.

It is evident that various changes might be resorted to in the construction, form and arrangement of the several parts for accomplishing the results herein stated; hence I do not wish to limit myself to the construction herein set forth, but

What I claim is:

- 10 1. In a machine of the character described, a reciprocating bed, a form thereon and inking mechanism therefor including a vibrator fixed against upward and downward movement, form rollers driven by the vibrator, and means independent of the bed for lowering the form rollers onto the form during the printing stroke and raising them from the form during the reverse stroke without disengaging them from the vibrator.
- 15 2. In a machine of the character described, a reciprocating bed, a form thereon, and inking mechanism therefor including a vibrator fixed against upward and downward movement, form rollers driven by the vibrator continuously in one direction and means independent of the bed for lowering the form rollers onto the form during the printing stroke and raising them from the form during the reverse stroke without disengaging them from the vibrator.
- 20 3. In a machine of the character described, a reciprocating bed, a form thereon, and inking mechanism therefor including an ink cylinder driven continuously in one direction, a vibrator driven thereby and fixed against upward and downward movement, form rollers driven by the vibrator and means independent of the bed for lowering the form rollers on to the form during the printing stroke and raising them from the form during the reverse stroke without disengaging them from the vibrator.
- 25 4. In a machine of the character described, a reciprocating bed, a form thereon and inking mechanism therefor including an ink cylinder driven continuously in one direction, a vibrator driven thereby and fixed against upward and downward movement, 45 form rollers driven by the vibrator and rotary means for lowering the form rollers on to the form during the printing stroke and raising them from the form during the reverse stroke without disengaging them from the vibrator.
- 30 5. In a machine of the character described, a reciprocating bed, a form thereon, and inking mechanism therefor including a vibrator fixed against upward and downward movement, form rollers driven by the vibrator continuously in one direction and rotary means for lowering the form rollers on to the form during the printing stroke and raising them from the form during the reverse stroke without disengaging them from the vibrator.
- 35 6. In a machine of the character described, a reciprocating bed, a form thereon and inking mechanism therefor including an ink cylinder driven continuously in one direction, a vibrator driven thereby and fixed against upward and downward movement, 55 form rollers driven by the vibrator and rotary means for lowering the form rollers on to the form during the printing stroke and raising them from the form during the reverse stroke without disengaging them from the vibrator.
- 40 7. In a machine of the character described, a reciprocating bed, a form thereon and inking mechanism therefor including an ink cylinder driven continuously in one direction, a vibrator driven thereby and fixed against upward and downward movement, form rollers driven by the vibrator and rotary means for lowering the form rollers on to the form during the printing stroke and raising them from the form during the reverse stroke without disengaging them from the vibrator.

4. In a machine of the character described, a reciprocating bed, a form thereon, and inking mechanism therefor including a vibrator fixed against upward and downward movement, form rollers driven by the vibrator and rotary means for lowering the form rollers on to the form during the printing stroke and raising them from the form during the reverse stroke without disengaging them from the vibrator.

5. In a machine of the character described, a reciprocating bed, a form thereon, and inking mechanism therefor including a vibrator fixed against upward and downward movement, form rollers driven by the vibrator continuously in one direction and rotary means for lowering the form rollers on to the form during the printing stroke and raising them from the form during the reverse stroke without disengaging them from the vibrator.

6. In a machine of the character described, a reciprocating bed, a form thereon and inking mechanism therefor including an ink cylinder driven continuously in one direction, a vibrator driven thereby and fixed against upward and downward movement, form rollers driven by the vibrator and rotary means for lowering the form rollers on to the form during the printing stroke and raising them from the form during the reverse stroke without disengaging them from the vibrator.

In testimony that I claim the foregoing as my invention, I have signed my name in presence of two witnesses, this thirteenth day of December A. D. 1910.

HOWARD M. BARBER.
